[57] CLAIM

The ornamental design for a fishing rod case, substantially as shown and described.

DESCRIPTION

FIG. 1 is a perspective view of a fishing rod case, showing my new design.

FIG. 2 is an enlarged scale cross sectional view taken along line 2—2 of FIG. 1; and

FIG. 3 is a perspective view of a modified form of the fishing rod case.

The sides of the fishing rod case opposite those shown in FIGS. 1 and 3 are substantially mirror images thereof except that the narrow end is plain.
